CLAIM

The ornamental design for a sun cover with mask as shown.

DESCRIPTION

FIG. 1 is a front perspective view of the sun cover with mask;

FIG. 2 is a front view thereof;

FIG. 3 is a back view thereof;

FIG. 4 is a top view thereof;

FIG. 5 is a side view thereof;

FIG. 6 is a perspective view of the sun cover with mask being worn with the mask lowered onto the neck;

FIG. 7 is a perspective view thereof; and,

FIG. 8 is a front view thereof.

The smaller evenly dashed broken lines along the surfaces of the sun cover with mask depict claimed stitching. The broken line outline of the partial human figure in FIGS. 6-8 assists in illustrating how the sun cover with mask may appear when in a position of use, but forms no part of the claimed design.
